SUCTION DUSTER FOR VENETIAN BLINDS

Earl C. Westhoff, Belton, and Jesse J. Williams,
Kansas City, Mo.

Application March 11, 1950, Serial No. 149,064

5 Claims. (Cl. 15—394)

1

This invention relates to suction dusters for Venetian blinds and more particularly to such a duster for use with suction cleaning apparatus such as vacuum cleaners.

The objects of the present invention are to provide a suction duster attachment for connection to a suction cleaner hose, the attachment having a head provided with removable cleaning or dusting elements for engaging opposite sides or faces of slats of a Venetian blind whereby the dusting elements loosen dirt on the blinds and said dirt is drawn into a hose along with air which is drawn through the dusting elements adjacent the faces of the slat being cleaned; to provide a suction duster having spaced parallel tubular members or branches adapted to straddle a slat of a Venetian blind to be cleaned, each of said branches having spaced dusting elements removably mounted thereon with slots between the dusting elements communicating with a suction cleaner hose connection; to provide a suction duster having spaced parallel slotted branches each of which has cylindrical recesses or sockets substantially parallel with the slots for removably mounting dusting elements therein; to provide dusting elements having sheep wool spirally mounted thereon adapted to be removably mounted in the sockets of the branches whereby the walls of the sockets tend to turn the fibers of the sheep wool toward the slats being cleaned to increase the density of the fibers engaging said slats; to provide sockets in the branches whereby the walls of the sockets and the fibers of the dusting elements substantially prevent free flow of air to the slots except through the fibers and along the faces of the slat being cleaned; to provide a relationship between the walls forming the sockets for the dusting elements and the slots whereby the walls define converging orifices to the slots which are spaced from the slats being cleaned so the sheep wool fibers will not enter and obstruct or close the slots; and to provide a suction duster of this character which is relatively simple, economical, durable, and highly efficient and in which the dusting elements may be removed and turned to place different surfaces of said elements in operation for dusting of Venetian blinds.

In accomplishing these and other objects of the present invention, we have provided improved details of structure, the preferred form of which is illustrated in the accompanying drawings, wherein:

Fig. 1 is a perspective view of a suction duster constructed according to the present invention shown engaging a slat of a Venetian blind.

2

Fig. 2 is a perspective view of the suction duster head with the dusting elements shown in spaced disassembled relation.

Fig. 3 is a vertical cross sectional view through the suction duster head on the line 3—3, Fig. 4.

Fig. 4 is a transverse sectional view through the suction duster head on the line 4—4, Fig. 3.

Fig. 5 is a horizontal sectional view through the suction duster head between the parallel branches thereof.

Fig. 6 is a partial transverse sectional view illustrating a dusting element being inserted in a socket in the head.

Referring more in detail to the drawings:

- 15 1 designates a suction duster having a tubular member 2 provided with an end 3 adapted for attachment to one end 4 of a hose of a suction cleaning device such as a vacuum cleaner (not shown). The tubular member 2 is preferably formed of plastic whereby the device may be molded in the shape desired and have relatively thin walls 5 defining a central passage 6 through the tubular member and ribs 7 on the walls to give sufficient strength thereto.
- 20 25 The tubular member 2 terminates in a head 8 which is slotted inwardly from the end thereof to form spaced parallel branches 9 and 10 arranged at an angle to the tubular member 2, and adapted to straddle a slat or louver 11 of a Venetian blind or the like which is usually held between supporting tapes 12 and 13 on the respective sides of the slat. The branches 9 and 10 are preferably molded integrally with the tubular member 2 and each preferably consists of a wall 14 formed in a U-shape with the legs 15 thereof extending toward the other branch and terminating in arcuate walls 16 forming laterally spaced cylindrical sockets 17 for receiving duster elements 18 as later described. A web 19 connects the walls 16 of the respective socket members of each branch whereby the U-shaped wall 14, web 19 and portion of the walls 16 define elongate passages 20 and 21 in the respective branches 9 and 10, said passages communicating as at 22 with the central passage 6 of the tubular member 2.
- 30 35 40 45

In order to facilitate molding of the portions of the branches 9 and 10, the outer ends thereof are preferably open and cap members 23 are suitably secured by cement or the like in the ends of said branches to close same. The outer contour of each of the caps preferably conforms to the contour of the outer surface of the wall 14 and wall 16, the cylindrical side portions 24 closing the ends of the sockets 17, the adjacent edges 25 of the cap members being on a line tangential with the cylindrical portions 24 whereby the

spacing between the cap members defines the entrance into the space between the branches for slats to be cleaned.

The cap members include extensions 25 which extend into the passageways 20 and 21 of the respective branches, thereby defining shoulders 26 adapted to engage the ends 27 of the walls 14 and 16. A web 28 also extends inwardly from the extensions 25 substantially in alignment with the web 19 between the walls 16 and terminates in a flange 29 which projects toward the space between the branches, the sides 30 of the flange 29 engaging the walls 16 and being suitably secured thereto whereby said flange forms the outer terminus of a slot 31 formed in the web 19. The slots 31 are so shaped as to be of increasing width toward the free ends of the branches and have an effective length slightly less than the width of the slats to be cleaned. Also the arrangement of the cap 23, web 28 and flanges 29 defines lateral channels 32 which coincide with notches 33 cut in the inner portions of the walls 16 whereby the channels communicate with the sockets 17 as later described.

The tubular member 2 is closed between the branches 9 and 10 by a wall 34 and the outer surface thereof is covered by a cushioning material, such as felt 35, to prevent contact of the Venetian blind slat 11 with the walls, thus preventing marring and scratching of the finish on said slats. The inner ends of each of the sockets 17 are closed by a wall 36 substantially in alignment with the wall 34 and the outer surface of said wall 36 is provided with a recess 37 substantially coaxial with the respective cylindrical socket to aid in retaining the dusting elements 19 therein, the walls 34 and 36 being so arranged that all air passing into the passage 6 of the tubular member 2 must be drawn from between the branches 9 and 10 through the slots 31 and through the passages 20 and 21 to said passage 6.

Each of the dusting elements preferably consists of a cylindrical core 38 having sheep wool 39 spiraled thereon and secured by cement or the like. The ends of the sheep wool are cut square with the ends of the cylindrical core 38 and resilient or cushion pads 40 are cemented or otherwise secured on the ends of the cylindrical core 38, the dusting elements being of such length that one of the pads 40 will engage one end of the sockets 17 as defined by the cap 23 and the other pad at the other end of the cylindrical core will seat in the respective recess 37 with some compression of the resilient felt or cushion pads to provide friction for retaining the dusting elements in the sockets. Also the walls 16 are so shaped that the diameter of the sockets are sufficiently larger than the cylindrical cores 38 whereby the fibers of the sheep wool may be compressed toward one side by the terminal edges 41 of the walls 16 as the dusting elements are inserted into the sockets through the spaces between the edges 41 of the walls 16, said spaces forming the openings 42 to the respective sockets 17 and when the dusting elements are seated in said sockets the size of the cylindrical cores 38 together with the wool fibers compressed between said cylindrical cores and the walls 16 will form snug fits for the dusting elements, tending to retain same in the sockets.

It is preferable that the plastic material from which the tubular member 2 and branches 9 and 10 are molded has a slight resiliency whereby the walls 16 extend more than a half circle and the openings 42 are less than the diameter of said

socket, thereby providing a gripping action by the ends of the walls 16 to aid in retaining the dusting elements in the sockets.

When the dusting elements are located in the sockets, the wool fibers extend from the openings 42 forming a dense, fibrous dusting medium directed toward a slat between the branches 9 and 10 for cleaning and the walls 16 define converging orifices leading to the slots 31 and the wool fibers are held by said walls at a distance from the slots, thereby preventing the wool fibers from entering and obstructing or closing said slots. The walls 17, being notched as at 33, allow the fibers to extend through the channels 32 to substantially obstruct and close the opening between the branches at the outer ends thereof. The dusting elements are removable from the sockets 18 for individual cleaning and also for turning said dusting elements to present a different surface to the slats to be cleaned whereby the entire cylindrical dusting elements give long wear but can be easily replaced when all of the fibers surrounding same are worn.

When the suction duster attachment is connected to a suction hose by suitably engaging the end 3 of the tubular member 2 on the end 4 of the suction hose and said suction duster applied to the slats or tapes of a Venetian blind by moving the branches transversely of the slats whereby the branches straddle same, the slat will be positioned between said branches and engaged by the fibers of the dusting elements as illustrated in Figs. 3 and 4. The suction draws air through the fibers and adjacent the faces of the slats being cleaned, then through the elongate converging orifices to the slots 31, through the passages 20 and 21 to the passage 6, and then through the hose to the suction cleaning device. As the suction duster is moved along the slat or tape, the dusting elements, and particularly the wool fibers thereon, will loosen and wipe dirt from the faces of the slats and that loosened dirt is drawn by the suction along the faces of the slats through the wool fibers and into the slots 31. Also the movement of air through the wool fibers tends to vibrate said fibers which helps to free the fibers of dirt and provides an additional movement of the fibers relative to the slats that aids in loosening dirt therefrom, regardless of the transverse contour of the slats whether they be flat, curved or V-shaped. Also the taper of the slots 31 is such as to provide substantially even distribution of the suction and movement of air therein so the movement of air relative to the slats and particularly over the face thereof is uniform.

The arrangement of the dusting elements in a cylindrical shape and having sheep wool fibers extending outwardly completely therearound and the placing of the dusting elements in the sockets 17 causes the edges of the walls 16 defining the opening 42 to compress said fibers to form a more compact portion of the fibers for wiping and contacting the faces of the slats. Any dirt adhering to the fibers may be easily cleaned therefrom by dipping the end of the suction duster into gasoline or other cleaning liquid and then shaking the cleaning liquid and dirt therefrom. For a more thorough cleaning, the fibers adjacent the outer end of the dusting elements are grasped and pulled outwardly relatively to the openings 42 to draw the end of the dusting element from the socket 17 whereby said dusting element may be removed and completely cleaned by water, solvent or the like. After cleaning the dusting element may be reinserted into the socket, preferably

by placing the end adjacent the wall 36 into the socket and then pressing the outer end inwardly into the socket, whereby the felt ends on the cylindrical core 38 will engage the ends of the socket to retain the dusting element in position. After a portion of the fibers have become worn, the dusting element may be removed and turned to present a new portion of the fibers for contact with the slats to be cleaned. Obviously after the entire dusting element has become worn, it may be easily replaced with a new element.

The dusting elements are so located that the wool fibers extend from the sides of the branches whereby the heavier member forming the base of the Venetian blind may be cleaned by turning the suction cleaner on its side, in engagement with said base member to loosen the dust on same and there will be sufficient suction of air through the wool fibers to carry the dust to the vacuum cleaner or the like.

It will be obvious from the foregoing that we have provided an improved suction duster attachment for vacuum sweepers and the like adapted for cleaning Venetian blinds which may be quickly applied to the sweeper hose and the blinds cleaned while in hanging position by the user while standing on the floor of the room from which position the uppermost louvers may be easily reached.

What we claim and desire to secure by Letters Patent is:

1. A suction duster for Venetian blinds comprising, a tubular member adapted for connection at one end thereof with a source of suction, spaced parallel hollow branches on the other end of said tubular member and adapted to straddle the slats of a blind, said branches having communication with the tubular member, a plurality of dusting elements having sheep wool thereon, and arcuate members adjacent to and extending along each side of each branch and forming exterior open-sided sockets for receiving and retaining said dusting elements whereby the fibers of the sheep wool engage the faces of a slat between the branches, the sockets in each branch being contiguous to the corresponding sockets in the opposed branch, said branches having slots only along adjacent faces of said branches between the dusting elements, said arcuate members forming elongate orifices leading to the slots and converging in a direction normal to said branches, said slots having a length relative to the width of the slats to be cleaned to confine the suction to the portion of the duster contacting said slats.

2. A suction duster for Venetian blinds comprising, a tubular member adapted for connection at one end thereof with a source of suction, spaced parallel hollow branches on the other end of said tubular member and adapted to straddle the slats of a blind, said branches having communication with the tubular member, a plurality of cylindrical dusting elements having sheep wool thereon, and arcuate members extending along each side of each branch and forming exterior open-sided laterally spaced sockets for receiving and resiliently retaining said dusting elements whereby the fibers of the sheep wool engage the faces of a slat between the branches, the sockets in each branch being contiguous to the corresponding sockets in the opposed branch, said branches having slots only along adjacent faces of said branches between the dusting elements, said arcuate members forming elongate orifices converging in a direction normal to the hollow branches and leading to the slots from adjacent a slot be-

tween the branches, said slots being of increasing width toward the free ends of the branches and having a length relative to the width of the slats to be cleaned to confine the suction to the portion of the duster contacting said slats.

3. A suction duster for Venetian blinds comprising, a tubular member adapted for connection at one end thereof with a source of suction, spaced parallel tubular branches on the other end of said tubular member and adapted to straddle the slats of a blind, said branches having communication with the tubular member, arcuate members extending along each side of each branch and forming exterior open-sided cylindrical sockets, the sockets in each branch being contiguous to the corresponding sockets in the opposed branch, means closing the ends of the cylindrical sockets, and a plurality of cylindrical sheep wool dusting elements removably mounted in the sockets and resiliently engaged by the arcuate members, said sheep wool fibers being compressed by the arcuate members and directed from the exterior open-sided cylindrical sockets for contacting a slat to be cleaned between the branches, said branches having slots only along adjacent faces of said branches between the dusting elements, said slots having a length relative to the width of the slats to be cleaned to confine the suction to the portion of the duster contacting said slats.

4. A suction duster for Venetian blinds comprising, a tubular member adapted for connection at one end thereof with a source of suction, spaced parallel tubular branches on the other end of said tubular member and adapted to straddle the slats of a blind, said branches having communication with the tubular member, arcuate members extending from each side of each branch and forming exterior open-sided cylindrical sockets, the sockets in each branch being contiguous to the corresponding sockets in the opposed branch, means closing the ends of the cylindrical sockets, a plurality of cylindrical sheep wool dusting elements removably mounted in the sockets and resiliently engaged by the arcuate members, and resilient members on the ends of the cylindrical elements for engaging the means closing the ends of the sockets to aid in retaining the dusting elements in said sockets, said sheep wool fibers being compressed by the arcuate members and directed from the exterior open-sided cylindrical sockets for contacting a slat to be cleaned between the branches, said branches having slots only along adjacent faces of said branches between the dusting elements, said slots having a length relative to the width of the slats to be cleaned to confine the suction to the portion of the duster contacting said slats.

5. A suction duster for Venetian blinds comprising, a tubular member adapted for connection at one end thereof with a source of suction, spaced parallel tubular branches on the other end of said tubular member and adapted to straddle the slats of a blind, said branches having communication with the tubular member, arcuate members extending from each side of each branch and forming exterior open-sided cylindrical sockets, the sockets in each branch being contiguous to the corresponding sockets in the opposed branch, means closing the ends of the cylindrical sockets, a plurality of cylindrical members, sheep wool spiraled around said cylindrical members to form cylindrical sheep wool dusting elements removably mounted in the sockets and resiliently engaged by the arcuate members, and resilient members on the ends of the cylindrical

members for frictionally engaging the means closing the ends of the sockets to aid in retaining the dusting elements in said sockets, said sheep wool fibers being compressed by the arcuate members and directed from the exterior open-sided cylindrical sockets for contacting a slat to be cleaned between the branches, said branches having slots only along adjacent faces of said branches between the dusting elements, said slots being of increasing width toward the free ends of the branches and having a length relative to the width of the slats to be cleaned to confine the suction to the portion of the duster contacting said slats.
